V. D. BARKER
FLUID DISPENSING APPARATUS

2,288,880

Filed May 16, 1940

FIG. I.

INVENTOR:
VIRGIL D. BARKER,
BY *Arthur E. Paige,*
Attorney.

UNITED STATES PATENT OFFICE

2,288,880

FLUID DISPENSING APPARATUS

Virgil D. Barker, Westfield, N. J.

Application May 16, 1940, Serial No. 335,474

1 Claim. (Cl. 221—73.5)

Although not limited to any particular embodiment, my invention may be advantageously embodied in apparatus for dispensing air at an automobile service station. At such a station, compressed air is principally used for operation of elevators to lift vehicles to permit them to be greased with facility; to dispense grease under pressure to the bearings of such vehicles, and to inflate the vehicle tires. It is ordinary practice to highly compress air, say to 150 pounds per square inch, by a pump operated by an electric motor, and to store it in a supply tank from which it may be released through dispensing apparatus which is adjustable to predetermine the pressure to which any air receiver may be charged.

Letters Patent of the United States No. 2,162,474 was granted June 13, 1939, to me for Fluid dispensing apparatus, of the class above contemplated and operative to dispense compressed air by a succession of pulsations until the back pressure through the dispensing conduit reaches that to which the controlling means is adjusted. That apparatus includes two control valves (shown in Fig. VI) each separately spring pressed toward its closed position but adapted to be automatically opened, by compressed air operating through lever linkages, to dispense the highly compressed air in such pulsations, through the dispensing conduit, until the selected pressure, variably predetermined by manual adjustment of a spring, is attained in the tire or other air receiver. In that patented structure the two valves are operated in proper sequence by respective rocker cams, in cooperative relation with respective rocker cam levers, carrying respective rollers, which are independently spring stressed into cooperative relation with the rocker cams. It is the object and effect of my present invention to simplify the construction, arrangement, and method of operation of that patented structure by substituting different actuating means for one of said valves, in lieu of the rocker cam, lever, roller, spring, etc., whereby it is adapted to be actuated in said patented structure; thereby effecting the elimination of six parts of the patented valve actuating means, viz., those marked 11^a, 48, 56, 56^a, 58, and 59, in Fig. III of said patent.

My invention operates in positively controlled cycles of pulsating charges of fluid to a receiver; each charge of fluid being terminated at a regularly uniform interval after its initiation, independently of either the back pressure in the receiver or the fluid resistance in the service conduit. In addition, my device does not require

any appreciable energy drain from, or reduction in, available pressure of a fluid to be delivered to the receiver. This is accomplished by utilizing the energy of the fluid directly from the source to furnish power for operating the apparatus, which fluid is subsequently exhausted to atmosphere.

As hereinafter described, the embodiment of my present invention illustrated includes two separate and distinct diaphragm chambers each containing a flexible diaphragm, the fluid pressure upon which is opposed by separate and distinct springs; one of said diaphragms being subjected to fluid pressure from the air dispensing conduit and the other of said diaphragms being subjected to fluid pressure directly from the supply reservoir. Moreover, the present invention provides a simplified construction and arrangement of controlling valve actuating means operatively connected with said two diaphragms and their springs for adjustably controlling the dispensation of the fluid.

My invention comprises the various novel features of construction and arrangement and method of operation hereinafter more definitely specified and including a bell signaling device for manifesting each pulsation of the apparatus during a dispensing operation.

In said drawing, 30 Fig. I is a rear elevation of a casing, connected with a conduit leading from the fluid supply reservoir and a fluid dispensing conduit, inclosing the two diaphragms and having, on the front thereof, indicating mechanism, not shown herein, 25 including a plurality of adjustable numbered wheels; said casing supporting the signal bell and means for operating it.

Fig. II is a longitudinal sectional view of the valve casing shown in Fig. I.

40 In said drawing, the main casing 1 incloses two diaphragm chambers 2 and 3, each containing a reciprocatory diaphragm, respectively 4 and 5. The fluid pressure supply conduit 6 from any suitable source of highly compressed air, supplies such air to said diaphragm chambers under automatic valve control, as hereinafter described. The fluid pressure service conduit 8 leads from said chamber 3 and the compressed air is dispensed through it. For the purpose of servicing

50 and inflating automobile tires, said service conduit 8 may have a dispensing hose connected therewith having at the end thereof a suitable connector or chuck for convenient attachment to a tire valve stem. Such chuck embodies a spring 45 pressed valve which closes to prevent air from

escaping from the hose when not attached to a tire stem, but is automatically opened and automatically unseats the tire valve when the chuck is properly applied to the tire valve stem.

Said diaphragm 5, which is subjected to the fluid pressure in said service conduit 8 has operatively connected therewith the reciprocating plunger 10. The bell crank lever 11, which is fulcrumed on the shaft 12 in bearings 13, 13' in said casing 1, has its short arm 11' in cooperative relation with said plunger 10 and has its long arm 11'' connected with the right hand end of the spring 15. The left hand end of said spring 15 carries the nut 16 which is in threaded engagement with the adjusting screw 17 cut on the shaft 18 extending exterior to said casing 1 and provided with the crank handle 19 by which it may be adjusted. That is to say, the stress of said spring 15 may be increased by turning said crank 19 clockwise or decreased by turning it counterclockwise.

I find it convenient to connect with said shaft 18 indicating means for manifesting in pounds the pressure of fluid to be dispensed for which said spring 15 is manually adjusted. Such means includes the gear pinion 21 on said shaft 18, and the intermediate gear 22 which meshes with the indicator mechanism gear 26.

When the crank handle 19 is turned by the operator, the gear 26 turns the indicating mechanism which, as disclosed in detail in my Patent 2,162,474 aforesaid, includes three wheels each having on its circumference a series of numbers from 1 to 9 inclusive and 0. The first of said wheels, which indicates individual pounds, is connected, by tens transfer gearing, with the second numbered wheel each of the numbers on which represent tens of pounds, and that wheel is connected, by tens transfer gearing, with the third numbered wheel each of the numbers on which represents hundreds of pounds. That arrangement is such that upon a complete rotation of the successive numbered wheels of lower order, the wheel of the next higher order is turned one-tenth of a revolution. Consequently, when the operator turns the crank handle 19 the three numbered wheels indicate the pounds pressure to which the apparatus is set by the screw 17 stressing said spring 15 to move said bell crank lever 11. For instance, in the position shown, the screw 17 has been manually adjusted to insure dispensation of compressed air through the service conduit 8, to charge an automobile tire or other receptacle with a pressure of thirty-five pounds per square inch.

Said supply conduit 6 is connected with the valve casing 40 in communication with the fluid passage 41 therein which connects with the parallel fluid passageways 42 and 43 in said casing 40. The air conduit 45 extends from said passageway 42 to the T-fitting 45' which opens into the diaphragm chamber 2, beneath said diaphragm 4. Said fitting 45' has the vent nozzle 45'' leading therefrom to the atmosphere and the vent 45^a therethrough is very much smaller than the cross sectional area of the conduit 45 and passageway 42; the purpose of said vent being to slowly bleed the fluid pressure from beneath said diaphragm 4 when the latter is not held up by fluid pressure through said conduit 45. Passage 70 of the high pressure air from said supply conduit 6 to said diaphragm chamber 2 is controlled by the reciprocating valve 46 which may be opened by the slidably fitted push rod 46' extending through the bearing 40' on said valve casing 40.

Push rod 46' is pivotally connected, by the link 47, directly with said bell crank lever long arm 11''; whereby opening movement of said valve 46 is initiated as hereinafter described.

Said diaphragm 4, which is subjected to the high pressure in said supply conduit 6, when said valve 46 is open, has operatively connected therewith the reciprocating plunger 49. The bell crank lever 50, which is fulcrumed on the shaft 51 mounted in bearings 52, 52' in said casing 1, has its short arm 50' in cooperative relation with said plunger 49 and has its long arm 50'' connected with the left hand end of the spring 54. The right hand end of said spring 54 is connected with the stationary anchor stud 55 in said casing 1. The effect of that arrangement is that the long arm 50'' of said bell crank lever 50 is moved to the left in Fig. I when said valve 46 is open and the fluid pressure in the diaphragm chamber 2 beneath the diaphragm 4 overcomes the stress of said spring 54, but, when said valve 46 is closed, that pressure is exhausted through said vent 45^a and the stress of said spring 54 moves said lever 50 clockwise to the position shown in Fig. I, where it is stopped by the stop stud 50^b fixed in said casing 1.

Referring to Fig. I; high pressure air is supplied from said conduit 6 to the diaphragm chamber 3 and service conduit 8 through the supply conduit 6' which has its upper end connected with said valve casing 40 in communication with the air passage 43, and has its lower end connected with the T-fitting 8' which is connected with said diaphragm chamber 3 and with said service conduit 8. The passage of high pressure air from said supply conduit 6 through said passageway 43 to said diaphragm chamber 3 and service conduit 8, is controlled by the valve 61 which has the push rod 61' extending through the stuffing box 40' on said valve casing 40 to open it and the spring 61^a to shut it. Said push rod 61' is pivotally connected, by the link 62, with the rocker cam lever 63 which is mounted to oscillate on the stationary fulcrum stud 57 fixed in said casing 1. Said cam lever 63 has at its upper end the pointed cam 63' and is adapted to be snapped clockwise to open said valve 61, and to be snapped counter-clockwise, to permit said valve to close. Such snap action is effected by the cam roller 63^a which is carried by the cam roller lever 65. Said lever 65 is fulcrumed on the stud 59^a fixed in the long arm 50'' of the lever 50. The opposite end of said lever 65 is connected by the spring 66 with the anchor stud 60 fixed in the casing 1, to continually stress said cam roller 63^a into cooperative relation with the face of said pointed cam 63'.

The combined effect of the two bell crank levers 11 and 50, their springs 15 and 54, and the lever linkage connecting them in the cooperative relation above described, is to dispense the highly compressed air, in pulsations, through the service conduit 8, until the selected pressure, variably predetermined by the adjustment of said screw 17, is attained in the tire, or other air receiver, and, with the adjustment indicated, that pressure would be thirty-five pounds per square inch; whereupon, the instant dispensing operation is automatically terminated.

In order to manifest to the operator the fact when any dispensing operation is continuing; I find it convenient to provide an audible signaling device which is sounded at each pulsation when said cam 63 snaps clockwise. Such a device is shown in Fig. I including the bell 63

(which is supported on the standard 69 fixed on the front of casing 1), and the clapper comprising the striker 70 and clapper lever 70', which latter is fulcrumed on the stud 71, which is stationary on the front of casing 1, as indicated in Fig. I.

Clapper lever 70' normally hangs loosely on stud 71 with its striker 70 in spaced relation with bell 68, as indicated in Fig. I, in position to be operated by the signal crank stud 72 which is fixed in rocker cam lever 63 and projects through the slot 73 in the front wall of casing 1. However, as roller 63^a and spring 66 turn cam lever 63, clockwise in Fig. I, each time said valve 46 is opened, by counterclockwise movement of rock lever 11, by spring 15; said signal crank stud 72 is carried by the cam lever 63 to the left in Fig. I and swings said clapper lever 70', and thus strikes the signal bell 68 with the striker 70; thus manifesting each pulsation of air dispensed. Therefore, when said audible signal ceases to sound, the operator is apprised that the instant dispensing operation is completed by the increment of pressure in the tire or other air receiver to the pressure for which the apparatus has been set by adjustment of said screw 17.

Referring to Fig. I; the stud 55, fixed in casing 1, limits the movement of bell crank lever 11 by spring 15, when the set screw 11^b encounters it. The stop stud 76, in casing 1, limits the movement of rocker cam lever 63, in opening valve 61.

To facilitate the assembling of valve casing 40 in the casing 1, I provide the slot 77, extending through valve casing 40 to receive bolt 78 fixed in casing 1. Said bolt is engaged by nut 78' to hold valve casing 40 in casing 1. As shown in Fig. II the left hand ends of the air passages 42 and 43 are respectively closed by the screws 80 and 81 and the latter has the cylindrical extension 81' which, as shown in Fig. I, fits in a hole 1' in said casing 1 to insure that said valve casing 40 shall be in proper vertical position. Said screws 80 and 81 are recessed to receive the outer ends of said valve springs 46^a and 61^a, the inner ends of which are respectively seated in recesses in said valves 46 and 61. Said springs continually tend to close said valves upon their seats in the casing 40. I prefer to provide a back cover plate 1^b for said casing 1, having a slot 16'' to guide the stud 16' on the nut 16 and prevent turning movement of the latter. Said plate is secured by the nut 1^b on the threaded end of the stop stud 76, indicated by dotted lines in Fig. I, and is prevented from turning by engagement of the anchor stud 55 in a hole in said plate.

Said apparatus may be operated as follows: The conduit 8 is connected, conveniently by a hose with a terminal chuck valve, to a tire or other air receiver containing less than the selected pressure of, say, thirty-five pounds, and air thus allowed to pass from diaphragm chamber 3 to such receiver. The air pressure within chamber 3 is thus reduced, and as that pressure approaches said selected pressure, spring 15 draws the upper arm 11'' of bell crank lever 11 to the left, in Fig. I. When the pressure in diaphragm chamber 3 is thus lowered to thirty-five pounds, lever arm 11'' has thus moved so far as to open valve 46, by thrusting link 47 and push rod 46' to the left. The highly compressed air is thus allowed to flow from the source through supply conduit 6 and passage

41, past valve 46 and through air conduit 45 and T-fitting 45' into diaphragm chamber 2, faster than it can escape through the restricted vent 45^a, flexing diaphragm 4 upward and forcing plunger 49 to turn bell crank lever 50 counterclockwise against the stress of spring 54. As the arm 50'' of lever 50 moves to the left it carries with it the stud 50^a and roller lever 65. Consequently, cam roller 63^a is drawn upward along the right hand incline of rocker cam 63'; pressing it counterclockwise. When roller 63^a passes over the crest of rocker cam 63' spring 66 snaps roller 63^a, by lever 65, downward along the left incline of cam 63', so as to turn cam lever 63 clockwise and snap link 62 and push rod 61' and valve 61 to the left, opening valve 61, until the lower end of cam lever 63 stops against stud 76. During that movement the signal is sounded by the crank 12 swinging the clapper lever 70' and 20 ringing the bell 68 with the striker 70.

Opening valve 61 allows the highly compressed air to flow from the supply conduit 6, through passage 43, conduit 6', T-fitting 8', conduit 8, hose and chuck valve, to the tire or other air receiver, and a certain amount of high pressure air also flows into the chamber 3. After cam roller 63^a thus passes to the left of the crest on rocker cam 63' unseating valve 61; the increase in air pressure from fitting 8' into chamber 3 lifts diaphragm 5, turns lever 11 clockwise, withdrawing push rod 46', by link 47, and thus permits valve 46 to be closed by its spring 46^a to thus stop the flow of compressed air to diaphragm chamber 2.

35 After the valve 46 is closed, air escaping from beneath diaphragm 4 through the restricted vent 45^a, reduces the pressure beneath the diaphragm 4; thus permitting bell crank lever 50 to be turned clockwise by the stress of its spring 54. As the latter motion occurs, cam lever 65 is thrust to the right, so that cam roller 63^a climbs up the left hand incline of rocker cam 63', pressing cam lever 63 clockwise. When roller 63^a passes to the right of the crest of cam 63', rocker cam lever 63 is snapped counter-clockwise by roller 63^a pulled down by spring 66, and valve 61 is permitted to be closed by its spring 61^a and stops the flow of air through valve 61 to conduit 6'.

40 If the pressure within the tire is yet less than the selected pressure, pressure within diaphragm chamber 3 will be reduced to below the selected pressure, by escape into the tire, and the cycle above described will be repeated until the pressure in diaphragm chamber 3 and in the tire and connecting conduits is equalized and then bell crank lever arm 11'' is held as in Fig. I, preventing another opening of the valve 46, and bell 68 is silent, indicating completion of the dispensation. Thereupon, conduit 8 may be disconnected from the tire, or other receiver, leaving the latter charged to very slightly above the selected pressure. Therefore, in such idle position of the apparatus, both of the valves 46 and 61 are closed and air of not less than the selected pressure is trapped in the diaphragm chamber 3; so that, when the pressure in chamber 3 is permitted to escape, as above-described, or otherwise, a dispensing operation is initiated, by operation of mechanism including bell crank lever 11, and such mechanism exemplifies the "means for initiating" contemplated in certain of the claims. The mechanism including bell crank lever 50 exemplifies what is termed in certain of the claims "power mechanism."

It is to be particularly noted that, whereas, in my patented apparatus aforesaid, the two valves 46 and 61 are both controlled by means actuated by the "power mechanism" lever 50; on the contrary, in this invention the valve 46 is controlled entirely independently of said lever 50, and solely by direct connection with the "means for initiating" lever 11.

However, I do not desire to limit myself to the specific details of construction, arrangement, or method of operation herein set forth, as it is obvious that various modifications may be made therein without departing from the essential features of my invention, as defined in the appended claim.

I claim:

In fluid dispensing apparatus, the combination with a conduit adapted for connection with

a receiver; of a first valve and a second valve in said conduit; spring-resisted fluid pressure operating means in operating relation to said second valve; spring-resisted pressure sensitive means, connected to said conduit, including a fluid chamber and a lever connected directly to said first valve which controls the supply of fluid to the fluid pressure chamber of said spring-resisted fluid pressure operating means in operating relation to said second valve; means for delaying the closing of said second valve, including a fluid pressure chamber having a restricted vent to atmosphere; and means connecting said fluid pressure chamber in controlling relation with said spring-resisted pressure sensitive means.

VIRGIL D. BARKER.
